UNITED STATES PATENT OFFICE.

GEORGE L. LANG, OF NEWARK, NEW JERSEY, ASSIGNOR TO SPLITDORF ELECTRICAL COMPANY, OF NEWARK, NEW JERSEY.

IGNITION SYSTEM.

1,295,528.

Specification of Letters Patent. Patented Feb. 25, 1919.

Application filed December 27, 1915. Serial No. 68,688.

To all whom it may concern:

Be it known that I, GEORGE L. LANG, a citizen of the United States, residing at Newark, in the county of Essex, and State of New Jersey, have invented certain new and useful Improvements in Ignition Systems, of which the following is a specification.

In starting internal combustion engines it is essential that the ignition sparks be obtained at low rotative speeds of the engine. This is particularly necessary where the grade of fuel is low or the engine large, such as those used for the heavier classes of stationary work.

It has been found that a magneto gives the highest grade of service in the matter of furnishing ignition for such engines after they have been started, but on account of the low rotative speed in starting, the magneto is somewhat deficient in its function of producing sparks for burning the poor mixtures that usually are obtained at the time of starting.

It is the object of my invention to overcome this difficulty by providing a means of obtaining sparks, no matter how slow the rotative speed of the engine is, while at the same time the magneto is used for producing the sparks after the engine has been started.

In order to accomplish the objects of my invention I provide a vibrator wired in circuit with a battery, which may be the battery that furnishes current for the starting motor which cranks the engine, as is common practice on automobiles, and an auxiliary circuit breaker which is used in conjunction with the main circuit breaker, and a switch for throwing the battery vibrator and auxiliary circuit breaker into circuit with the primary of the armature of a high tension magneto of the Siemens type, or through the primary of the coil of the inductor type.

It sometimes happens that the operator forgets to retard the spark in stopping his engine, and should the engine be again started on the vibrator if connected directly to the primary of the armature or coil, as is sometimes done, a back kick might result.

One of the objects of my invention is to overcome this difficulty; by arranging my auxiliary circuit breaker so that it always

operates after the main circuit breaker and consequently at a more retarded position.

Other and further objects of my invention will be apparent to any one skilled in the art after a study of this specification taken in connection with the drawing in which Figure 1 is a diagrammatic view of the apparatus and circuits used in my improved system. Fig. 2 is a partial sectional view through the breaker box on the line 2—2, but showing the parts of the main and auxiliary circuit breaker in elevation. Fig. 3 is an end view of the breaker box cover.

Referring now particularly to the drawings, 1 illustrates a breaker box having an advance lever 2. Mounted on the interior of the breaker box 1 is an insulated contact block 3 which carries the contact screw 4 that is locked in place on the block 3 by screw 5. A breaker arm 6 is pivoted at 7 on the breaker box. The movable breaker arm 6 carries a friction wearing element 8, such as fiber. Also a contact 9 which is adapted to coöperate with the contact screw 4. Spring 10 is used to return the breaker arm 6 after the same has been operated by cam 80 11 that is mounted on the magneto shaft 12. A spring 13 passes across the front of the cam 11 and over the pivot pin 7 for the purpose of holding the breaker arm 6 in position on its bearing. Attached to the breaker box 1 is a stud 14, but insulated therefrom by the bushing 16 and insulators 17. Mounted on this insulated stud 14 is a block 18 to which is attached a resilient member 19. The block 18 has a projection 90 20 that extends over the friction wearing element 8, and is adapted to be moved by the element 8 directly after the cam 11 strikes element 8. Attached to the breaker box 1, but insulated therefrom, is a second 95 stud 15 which carries a contact 21 adapted to engage contact 22 on resilient member 19. The studs 14 and 15 pass through insulating bushings 24 in breaker box cover 23 when the same is in position on the breaker box 100 1, so that electrical connection to these two studs can be made on the exterior of the breaker box cover 23 by means of contact nuts 27, shown in Fig. 2. 25 is an insulated contact fastened to the center of the breaker 105 box cover, and when the said cover is in position on the box a spring 26 makes contact on the interior of the cover extending con-

nection from the contact 25 to the contact block 3. The cover 23 is held on to the breaker box by a spring attached to an insulated stud on the magneto, one end of which spring rests against the outside end of the contact button 25. For the sake of clearness this spring which holds the breaker box 23 in position is not shown.

P illustrates the primary winding of a 10 coil, and S the secondary thereof. These coils may be included on the rotating armature, as in the Siemens type of high tension magneto, or they may be on a stationary structure, as in the inductor type of 15 magneto. It is understood that the outside terminal of the secondary is connected to a distributor for the purpose of distributing the sparks to the proper cylinders of the engine. V is a vibrator of any suitable 20 type, to which is connected the battery B that may be grounded on one side, as at G. 28 illustrates diagrammatically a switch for the purpose of switching the vibrator into circuit, as heretofore mentioned, or for 25 switching the magneto to the off or on position. As indicated the switch has three positions. M for the magneto, OFF for the non-running position, and B for battery position.

30 I will now describe the operation of my system.

Suppose it would be desirable to start the engine. The switch 28 is thrown to position B and the segment 32 will make 35 contact between the studs 29 and 30. Let it be assumed that the cam 11 has hit the fiber piece 8 and moved it sufficiently to cause it to lift on the nose of projection 20 of the auxiliary circuit breaker. When this 40 movement has progressed far enough, it will be seen that the contacts 5 and 9 are separated, but due to a low rotative speed of the magneto little or no spark is produced in the engine cylinder, it being 45 understood that the circuit breaker lever 6 is connected directly to the frame work of the magneto which is grounded whereby the primary winding of the coil is connected to ground at one end through the 50 circuit breaker in the usual manner, and then contacts 21 and 22 are closed. A circuit may now be traced from battery B through the vibrator to contact stud 14, resilient member 19, contacts 22 and 21, 55 stud 15, switch contact 29, across segment 32 to switch contact 30, back to contact 25 and spring 26 to contact block 3, and through the primary winding of the coil to ground.

60 The vibrator will begin to operate, sending a strong current through the primary of the coil, causing a shower of sparks to emanate from the spark plug in the engine cylinder having gas to be fired. When the 65 engine starts the switch segment 32 is

thrown to make contact with the switch post 31, but since the contact strip 32 does not touch contact 30 the magneto is left in its running position. When it is desired to stop the engine the switch 28 is thrown 70 to the off position so that segment 32 crosses the contacts 30 and 31 which grounds the free end of the primary winding of the coil direct thus shunting the circuit breaker, and no sparks are produced.

75 It is to be noted that the main circuit breaker, which produces the sparks under normal running conditions of the magneto, operates in advance of the auxiliary circuit breaker, which is used primarily for 80 starting on battery, although by moving the advance lever sufficiently far, the engine can be operated by the vibrator or by the magneto and vibrator acting one after the other. That is, should the magneto spark 85 proper, as produced by the main circuit breaker, fail to ignite the gas, the auxiliary breaker producing sparks succeeding those produced by the magneto, would fire the gas.

It will be understood that numerous 90 changes in the details may be made in the arrangement of the apparatus by any one skilled in the art, but I consider these changes and alterations as mere equivalents all of which I believe come within the scope 95 of the appended claims.

Having thus described my invention what I claim is:

1. In an ignition system, the combination of a generating coil having primary and 100 secondary windings, a main circuit breaker included in the circuit of said primary winding, a vibrator, a source of direct current, a second circuit breaker, a switch for connecting said last three mentioned elements in circuit with said primary winding through an element of the first mentioned circuit breaker, and a common means for operating both said circuit breakers.

105 2. In an ignition system, the combination of a generating coil having primary and secondary windings, a circuit breaker included in the circuit of said primary winding, a vibrator, a source of current, a second circuit breaker, a switch for connecting said 110 last three mentioned elements in circuit with said primary winding through an element of the first mentioned circuit breaker and means for first opening the first mentioned circuit breaker and then closing the second 115 breaker whereby interrupted current is sent through the primary winding for the purpose described.

120 3. In an ignition system, the combination of a generating coil having primary and 125 secondary windings, a breaker box structure carrying a main circuit breaker having fixed and movable contact members and an auxiliary circuit breaker also having fixed and movable contact members, said primary

winding having one end connected to the fixed contact of said main circuit breaker, a vibrator having one terminal connected to one of the members of the auxiliary circuit breaker, a switch for connecting the other member of the auxiliary circuit breaker to the fixed member of the main breaker, a battery adapted to be connected in circuit with said vibrator, and means for opening the main circuit breaker and then closing the auxiliary breaker whereby said vibrator sends current impulses through said primary winding for the purpose set forth.

4. In an ignition system, a magneto having a generating coil consisting of primary and secondary windings, a breaker box carried by said magneto, a main circuit breaker having a relatively fixed member and a movable member mounted on said breaker box, said members being in the normal operating circuit of said primary winding, an auxiliary circuit breaker mounted on said breaker box, a vibrator having a source of current connected thereto, said vibrator being connected to one of the members of said auxiliary circuit breaker, a switch connecting one of the members of said auxiliary circuit breaker to the relatively fixed member of the main circuit breaker, a cam driven by said magneto which first operates said main circuit breaker and then said auxiliary circuit breaker, whereby said vibrator is connected in circuit with said primary winding for the purpose set forth.

5. In an ignition system for explosion engines, a spark producing coil having primary and secondary windings, a pair of circuit controllers controlling different circuits, and a single means for operating said circuit controllers to first open one of said circuits and then to close a circuit through a portion of the circuit that has just been opened including said primary winding.

6. In an ignition system for explosion engines, a coil for producing sparks having primary and secondary windings, a circuit controller for interrupting a normal magneto circuit including said primary winding, a circuit controller for making and breaking a battery vibrator circuit through said primary winding, and a single means for actuating both of said circuit controllers successively, whereby the magneto spark is followed by the battery spark.

7. In an ignition system for explosion engines, a cam, a main circuit controller operated by said cam thereby to open a magneto primary circuit, a second circuit controller

operated by the first controller to close a battery circuit through said magneto primary circuit.

8. In an ignition system, a magneto having a generating coil with primary and secondary windings, a main circuit controller, normally in circuit with said primary winding, a cam for operating said circuit controller, an auxiliary circuit controller operated by said cam, said auxiliary circuit controller controlling a vibrator circuit through said primary winding, and a switch for switching said auxiliary circuit controller into and out of said primary circuit.

9. In an ignition system, a magneto having a generating coil consisting of primary and secondary windings, a main circuit controller permanently connected in circuit with said primary winding, a cam for operating said circuit controller, a second circuit controller operated by said cam, said second circuit controller operating to control the vibrator circuit through said primary winding.

10. In an ignition system for explosion engines, a coil for producing sparks in said engine, having primary and secondary windings, a pair of circuit controllers, and a single means for first operating one controller and then the other to open a circuit through said primary winding and then close a separate exciting circuit through said primary winding, for the purpose described.

11. In an ignition system, a magneto having a generating coil consisting of primary and secondary windings, a pair of circuit controllers, and a cam for operating both of said controllers, one after the other, whereby a circuit through said primary winding is opened and then closed, and a battery and vibrator adapted to be connected in said last mentioned circuit.

12. In an ignition system, a magneto having a generating coil consisting of primary and secondary windings, two circuit controllers, each adapted to control a circuit through said primary winding, a battery and inductorium, a switch to connect said battery and inductorium to an element of each circuit controller and common means for operating first one circuit controller and then the other whereby said battery and inductorium is brought into said primary winding circuit after the first controller is operated.

In witness whereof, I affix my signature.

GEORGE L. LANG.
